UNITED STATES PATENT OFFICE.

ROBERT S. MURPHY, OF DETROIT, MICHIGAN, ASSIGNOR TO THE ELECTROGRAPH COMPANY, OF DETROIT, MICHIGAN, A CORPORATION OF MICHIGAN.

PRINTING PRESS.

Application filed March 25, 1926. Serial No. 97,223.

My invention relates to printing presses and an object of my improvement is to provide an improved way of mounting and operating an inking ribbon through which the 5 impress of the type is to be made.

My improvement has been designed to be used in the apparatus described and claimed in a co-pending application, filed by James P. Beatty, and having the Serial Number 10 65,534, in connection with which apparatus it is herein shown.

In the drawings:

Figure 1, is a side elevation of a printing press with an apparatus embodying my invention thereon.

Figure 2, is a view to an enlarged scale of the frisket, frisket-bearing frame, and ribbon operating apparatus in said frame.

Figure 3, is a section on the line III—III, 20 Figure 2, looking in the direction of the arrows.

Figure 4, is a detail elevation of the upper roll-actuating apparatus looking from the right of Figure 2.

25 Figure 5, is a section on the line V—V, Figure 4.

Figure 6, is a plan view of the actuating apparatus shown at the upper right hand corner of Figure 2, and parts adjacent there- 30 to.

Figure 7, is an elevation, to an enlarged scale, of the lower roll and actuating parts thereof.

35 *a* is the platen, *b*, the bed and *c* the frisket-bearing frame of a printing press.

d, is an address-plate upon the platen *a*. *e*, is a block on the bed *b* presenting a platen surface to the plate *d*, and *c³*, *c⁴*, are double frisket sheets, having openings *c^{3a}*, and *c^{4a}*

40 through which the plate *d* prints upon a card placed upon the frisket sheet *c⁴* over the opening *c^{4a}*, as described more fully in the application above referred to. *f*, is a small type-form for printing the message.

45 The frame *c* is made up of uprights *u* *u*, a horizontal bar *h* rectangular in cross-section extending between the upper ends of said uprights and a similar bar *h²* extending between the lower ends of the same. The 50 bar *h* is provided with properly spaced vertically extending screw-threaded holes *ha*, (Fig. 6), along its centers and the bar *h²* is provided with horizontally extending slots *h^{2a}*, (Fig. 2).

j, *j*, are uprights extended horizontally 55 outward at their lower ends and provided with holes matching with the holes *ha*. *hj*, are screws passing through the holes in the horizontal parts of the uprights *j*, *j*, and engaging in screw holes *ha* to secure said 60 uprights on the upper surface of the bar *h* at the required position intermediate its ends. *j²*, is a drum or roller extending horizontally and bearing in the uprights *j*, *j*. *j³*, is a ratchet wheel secured to the roller *j²* 65 concentric therewith at one end of said roller. *j⁴*, is a pawl pivoted to an upright *j* and adapted to engage the teeth of the ratchet wheel *j³*, to prevent a reverse movement of the same. *m*, is an approximately 70 horizontal oscillating lever pivoted at its center upon the arbor of the drum *j²* and extended both ways therefrom. Upon the end toward the bed *b* said lever carries a head *j⁶* upon which is pivoted an actuating 75 pawl *j⁵*, which engages the teeth of the wheel *j³*. *mj⁹*, is a pin extending laterally from the lever *m*. *j⁷*, is a lever pivoted at *mj⁹* to an end of the lever *m* and having its angular movement in one direction limited 80 by the pin *mj⁹*. *mj⁸*, is a spring acting upon the lever *j⁷* to hold it yieldingly in contact with the pin *mj⁹*. The lower end of the lever *j⁷* is made concave at *j⁸* to adapt it to be engaged by the platen to oscillate said lever 85 and thereby the lever *m*, as indicated in broken lines in Figure 4.

j¹⁰, is a milled head adapted to rotate a short shaft bearing in the head *j⁶*. *j⁹*, is a cam upon the opposite end of said shaft 90 adapted to be rotated by the milled head *j¹⁰*, and when so rotated to turn the pawl *j⁵* about its pivot and disengage it from the teeth of the wheel *j³* and hold it disengaged. *j¹¹*, is a rod adapted to reciprocate through 95 an aperture in the standard *j* and having a cammed edge at one end adapted to engage the pawl *j⁴* and hold it out of engagement with the teeth of the wheel *j³*.

At the lower end of the frame *c*, there 100 are standards *k*, *k*, corresponding to the standards *j*, *j*, and a roller, and actuating mechanism therefor, entirely similar to that above described, except that the standards *k*, *k*, are secured to a flat bar *n* which is 105 provided with an attaching lug *n²* by which it is secured to the cross bar *h²* of said frame by a bolt *nh²*, passing through slots *n^{2a}*, at

any position desired, and the oscillating lever is provided with an integral extension k^7 , instead of the pivoted lever j^7 operated by a cord or wire q secured to the outer end 5 of said extension at one end and to a part of the press at the other end so that said wire shall be drawn upon at each operation of the press.

The parts at the lower end of the frame c 10 are indicated by the letter k with the figure indicating a part corresponding to that lettered j with the same figure at the top of the frame.

The lever m and the corresponding lever 15 km are returned to their normal positions by springs y and y^2 , after being actuated by the moving press.

c^2 , is an inking ribbon that is wound around the rollers j^2 and k^2 , passes through 20 slots c^{1b} and c^{4c} in one sheet of the double frisket and in front of the opening c^{2a} and c^{4a} .

The operation of the above described device is as follows:

25 The form and position of the address plate is adapted to the work to be done and the openings in the frisket sheet selected accordingly. The rollers are then secured in their proper positions on the cross bars 30 of the frame c with the ribbon secured to said rollers and passing in front of the opening in the frisket sheet.

If the ribbon is wound on the lower roller k^2 , the pawl k^5 is disengaged from the teeth 35 of the wheel k^3 by turning the cam k^9 by means of the milled head k^{10} , and the pawl k^4 by pressing the rod k^{11} inward is forced out of engagement with the teeth of said wheel and held.

40 The press is now operated, the edge of the platen a engaging the end j^8 of the lever arm j^7 , and oscillating the lever m , thus moving the ratchet wheel j^6 and roller j , a short distance at each stroke.

45 When the ribbon has been wound upon the roller j^2 , the pawls j^1 and j^5 are thrown out of engagement as above described for k^4 and k^5 and the last named pawls are caused to engage the teeth of the ratchet wheel k^3 .

50 Each time the press is operated the lever km is oscillated by drawing upon the wire

or cord q and the ribbon is rewound upon the roller k^2 .

What I claim is:

1. In an apparatus of the kind described, 55 the combination of a frisket frame, a frisket thereon, the frisket frame having upper and lower cross bars, horizontal rollers adapted to be secured at various positions intermediate the ends of said cross bars, a vertically 60 extending ribbon passing around said rollers and means for actuating said rollers to move the ribbon by the operation of the apparatus.

2. In an apparatus of the kind described, 65 the combination of a frisket frame having upper and lower cross bars, horizontal rollers on said cross bars, a vertically extending ribbon upon said rollers and means for actuating said rollers, and a frisket sheet on said frame said ribbon passing 70 through slots in said frisket sheet.

3. In an apparatus of the kind described, 75 the combination of a frisket frame, a frisket thereon, a platen, a horizontal roller and means for actuating the same on said frame, said actuating means being adapted to be actuated by contact with said platen and a vertically extending ribbon passing around said roller.

4. In an apparatus of the kind described, 80 the combination of a frisket frame, a frisket thereon, a platen, a horizontal roller on said frame, a jointed lever pivoted directly on said frame and adapted to be actuated by contact with the platen and to actuate said 85 roller and a vertically extending ribbon passing around said roller.

5. In an apparatus of the kind described, 90 the combination of a frisket frame, a frisket thereon, the frisket frame having upper and lower cross bars, horizontal rollers adapted to be secured at various positions intermediate the ends of said cross bars, a vertically 95 extending ribbon passing around said rollers and means for actuating said rollers to move the ribbon by the operation of the apparatus, and a frisket sheet having an opening c^{4a} therethrough for the purpose described.

In testimony whereof I sign this specification.

ROBERT S. MURPHY.
